UNITED STATES PATENT OFFICE.

ARTHUR MADDOCKS, OF DENVER, COLORADO.

MANHOLE COVER.

Application filed February 4, 1924. Serial No. 690,485.

To all whom it may concern:

Be it known that I, ARTHUR MADDOCKS, a citizen of the United States, residing at Denver, the city and county of Denver, 5 and State of Colorado, have invented certain new and useful Improvements in Manhole Covers; and I do declare the following to be a full, clear, and exact description of the invention, such as will enable 10 others skilled in the art to which it appertains to make and use the same, reference being had to the accompanying drawings, and to the characters of reference marked thereon, which form a part of this specification. 15

This invention relates to improvements in manhole covers and has special reference to means for locking the same in place.

In our cities there are a large number of 20 sewers, tunnels and conduits of various kinds, to which access is had through manholes. The manholes are located in the alleys and streets and are closed by strong cast-iron covers that rest on a flange secured to a ring. It frequently happens that 25 the covers are removed either accidentally or intentionally, with the result that serious accidents happen. Owing to the suction between the surface of the roadway and a 30 pneumatic automobile tire, it sometimes happens that the covers are removed from manholes by any rapidly passing automobile that may pass over them.

It is the object of this invention to produce a simple locking means, with which 35 any manhole cover can be equipped, and which will positively prevent the cover from becoming accidental removed.

Manholes are usually round openings with 40 sides of brick or concrete, to the top of which is secured a cast-iron ring having an inwardly extending flange upon which the cover rests. My invention, briefly described, 45 consists in providing the cover with a lug that will engage the under side of the flange, and which cooperates with a turn button secured to the cover at a point diametrically opposite to the lug. When the cover is in 50 place and the turn button moved into such a position that it will project under the flange, the cover will be locked against removal. I also provide means which will hold the turn button from accidental rotation 55 and which cannot be put into place until the turn button is in locking position.

My invention can be mostly clearly de-

scribed and will be most readily understood when reference is had to the accompanying drawing, in which the preferred embodiment thereof is illustrated, and in which:

Fig. 1 is a plan view of the top of a manhole with the cover in place thereon, a portion of the cover being broken away to show the flange;

Fig. 2 is a section taken on line 2—2, 65 Fig. 1, and shows the cover in locked position;

Fig. 3 is a section similar to that shown in Fig. 2, but with the parts shown on an enlarged scale;

Fig. 4 is a plan view of a portion of the cover shown in Fig. 3;

Fig. 5 is a bottom plan view of the locking plug; and

Fig. 6 is a section taken on line 6—6, 75 Fig. 5.

Numeral 1 represents the cast-iron ring that is secured to the top of the manhole wall. This ring has an inwardly projecting flange 2 upon which the cover 3 is supported. A lug 4 is secured to the underside of the cover by means of rivets 5. The end 6 of this lug is offset to such an extent that the space between it and the under side of the cover will receive the flange 2 in the manner shown in Figs. 2 and 3. Near the edge of the cover diametrically opposite from the lug 4, I drill a hole 7 and a larger hole 8 which intersects the hole 7 in the manner shown in Fig. 4. Underneath holes 7 and 8 I secure a plate 9 by means of rivets 10. Plate 9 is slightly thicker than the flange 2 and has an opening substantially centrally located with respect to the hole 8. A spindle 110 is rotatably mounted in the opening in plate 9. This spindle has a non-circular head 11 that projects into the hole 8. The head 11 is unsymmetrical with respect to one axis so that it will enter a correspondingly shaped hole in one way only. Non-rotatably secured to the outer end of spindle 110 is a turn button 12 which is of greater length than width so that it will, when in one position, project beyond plate 9 and engage the under side of flange 2 in the manner shown in Figs. 2 and 3. When the turn button is rotated 90 degrees, it will not project underneath flange 2. It is now apparent that when the cover is put in place with the end 6 of lug 4 projecting under the flange 2 and the turn button rotated into locking position, the cover will be positively

locked in place. I contemplate providing a socket wrench by means of which the head 11 may be engaged for rotating the spindle and the turn button, although this can, under ordinary circumstances, be accomplished by means of a pair of pliers. For the purpose of filling the opening 7 and 8 and for positively holding the turn button in locking position, I provide a plug 13 whose outer periphery is shaped to conform to the opening 7 and 8. On its lower side plug 13 has an opening 14 shaped to receive the head 11. As the plug can only be inserted into the opening in the cover in one way and as the head 11 will enter opening 14 in only one way, and since the opening 14 is so arranged with respect to the plug and the head 11 that the plug can only be put into place when the turn button is in locking position, it is evident that after the plug has been put into place, the cover cannot be unlocked without first removing the plug, thereby assuring that the cover cannot accidentally become unlocked. The upper side of the cover is provided with two depressions separated by a wall 15 that can be grasped by the fingers or by a pair of pliers, when the plug is to be removed.

From the above, it is evident that I have produced a simple means that can be cheaply applied to any existing cover, and which will positively hold the same against accidental

removal. Of course the locking means described, does not prevent a mischievous person, provided with the necessary tools, from removing the cover, but the labor required to remove the same is sufficient to deter any ordinary person from removing the cover, and as the lock is a positive preventive of accidental removal, the danger of accidents from this source is almost entirely removed wherever my locking means is employed.

Having now described my invention, what I claim as new is:

A manhole cover comprising a plate, a lug secured to one side of the plate near the outer edge thereof, said lug having a portion spaced from the surface of the plate so as to provide an opening for the reception of a flange, said cover having an opening near the side opposite from the lug, a plate secured to the underside of the cover and adapted to cover the opening, a turn button rotatably secured to said plate, means comprising a noncircular head secured to the turn button and accessible from the top of the plate for rotating the turn button, and means comprising a plug having an opening adapted to receive the head for holding said button-turning means against accidental movement when the button is in locking position.

In testimony whereof I affix my signature.
ARTHUR MADDOCKS.
